Fig.4

FIG. 1 is a perspective view of a covered storage partition for station wagons with the cover in its open position showing my new design adapted to fit over the left wheel well of a station wagon, it being understood that the broken lines are for illustrative purposes only;

FIG. 2 is a front elevational view thereof with the cover in its closed position;

FIG. 3 is a top plan view thereof with the cover in well of a station wagon; and

FIG. 4 is a bottom plan view thereof with the cover in its closed position;

FIG. 5 is a rear perspective view of a covered storage partition for station wagons showing a second embodiment of my new design adapted to fit over the right wheel well of a station wagon; and

FIG. 6 is a front elevational view of the embodiment shown in FIG. 5.

The bottom of the embodiment shown in FIG. 5 is substantially a mirror image of the bottom shown in FIG. 4.

I claim:

The ornamental design for a covered storage partition for station wagons, substantially as shown and described.
